Inventor
William F. Kiesel Jr.

UNITED STATES PATENT OFFICE.

WILLIAM F. KIESEL, JR., OF ALTOONA, PENNSYLVANIA.

FREIGHT TRUCK.

Application filed May 17, 1919. Serial No. 297,722.

To all whom it may concern.

Be it known that I, WILLIAM F. KIESEL, Jr., a citizen of the United States, and residing at Altoona, Blair County, State of Pennsylvania, have invented certain new and useful Improvements in Freight Trucks, of which the following is a specification.

The present invention relates to car trucks and more particularly to six wheel trucks 10 for freight cars.

The principal novel features of this invention reside in the improved side frame members; the improved single piece bolster; the improved loose connection between the 15 bolster and side frames, this connection being the sole means for holding the side frames in proper spaced relation; the improved means for holding the central journal boxes against transverse movement, the equalizer 20 bars being utilized for this purpose; and the improved means for supporting one end of the equalizer bars on the side frame members. Other features of novelty will be apparent from the description taken in connection with the drawings, in which—

Fig. 1 is a top plan view of a truck constructed in accordance with the present invention, certain parts of one of the side frames being shown in section to illustrate 30 parts otherwise hidden;

Fig. 2 is a side elevation of the truck shown in Figure 1;

Fig. 3 is a sectional elevation through a portion of one of the side frames and associated parts taken substantially on line 3—3 of Figure 1, an equalizer bar being shown in 35 elevation;

Fig. 4 is a sectional elevation taken substantially on the line 4—4 of Figure 1;

Fig. 5 is a sectional elevation taken substantially on the line 5—5 of Figure 1;

Fig. 6 is a sectional elevation through the bolster taken substantially on the line 6—6 of Figure 1;

Fig. 7 is a sectional elevation thruogh the bolster taken substantially on the line 7—7 of Figure 1;

Fig. 8 is a sectional elevation taken substantially on the line 8—8 of Figure 7;

Fig. 9 is a top plan view of one of the central journal boxes illustrating the manner of supporting the adjacent end of the equalizer bars, one of the bars appearing in section; and

Fig. 10 is a sectional elevation taken substantially on the line 10—10 of Figure 3.

Referring to the drawings it will be seen that the truck embodying the present invention comprises the side frame members F and F' loosely held in spaced relation by 60 the single piece bolster B. The end axles A and A' support the side frames through journal boxes bolted to the under side of said frames. The central axle A² has journal boxes at its ends on which one end of 65 each of the equalizer bars E are supported, the other ends of the bars being carried by the frames.

As shown the side frames F and F' are hollow and substantially rectangular in cross 70 section. The cross sectional shape of the side frames may perhaps be best defined by the term box section. Furthermore, throughout the greater part of their length they are substantially straight. The end portions 75 of these frame members however are tapered and inclined downwardly to a slight extent. The frame members adjacent the bases of the tapered portions are supported on the journal boxes 20 of the end axles, these boxes 80 preferably being standard M. C. B. freight car boxes. The boxes are secured to the under side of the frame members by bolts 21, apertures 22 being provided in the bottom walls of the side frame members for these 85 bolts. In order to give access to the heads of the bolts 21, apertures 23 are provided in the top walls of the frame members, these apertures registering with the apertures 22. The ends of the frame members are forked 90 as at 24 and these ends are apertured as at 25 to provide means for supporting parts of the brake apparatus. Furthermore the tips of the tapered ends of the frames are offset as so that they are disposed very nearly in the 95 planes of the wheels of the truck as clearly shown in Fig. 1. The bottom walls of the side frame members are formed with the elongated slots 26, these slots being positioned over the journal boxes 27 of the central axle, for a purpose presently to be described. Adjacent the end boxes 20, the under side of each of the frame members is provided with the hollow depending projections 28. The equalizer bars E each have 100 one of their ends 30 disposed within a projection 28 and this end is formed with an aperture 31 for a key 32, the ends of which are disposed in the registering apertures 33 formed in the side walls of the projections. 105 As clearly shown in Figure 10, the under side of the key 32 is formed with a central 110

lug 34, the length of which is substantially equal to the distance between the side walls of the projections 28 whereby the lug 34 holds the key against displacement. The 5 apertures 33 are of greater height than the key, so that the key may be removed by first moving it vertically upward from its position in Figure 10 and then pushing it out laterally through one of the apertures 33.

10 As shown in Figure 9 the central box 27 is formed with the vertically disposed grooves 35 on its opposite vertical sides and recesses 36 in its top in line with the side grooves. The equalizer bars E are constructed to have one end thereof disposed in the said grooves and recesses. These ends of the bars are also provided with a projection 37 which is disposed within the slot 26 in the bottom of the frame member. In this 15 manner the adjacent ends of the equalizer bars act as keys to hold the central boxes 27 from transverse movement relative to the side frames.

The bolster is of one piece construction. 25 As shown it comprises the two transverse spring beams 38 of I section. These beams are connected by the longitudinal trusses 39, the latter being offset inwardly from the ends of the beams 38, so that they are disposed just inside of the wheels 40. As 30 clearly shown in Figures 6 and 7 each of these trusses are formed with a recess 41 in its under side for the passage of the axle A². A strap 42 is disposed across the mouth 35 of each of these recesses and secured to the under side of the trusses, as by means of bolts 43. The straps 42 are formed with the shoulders 44 which engage on the outside of the lugs 45 at the mouth of the recesses, 40 thus providing a connection between the truss and strap acting to prevent the mouth of the recess from being opened up when the truss is stressed, and thus relieving the bolts 43 from carrying all of this load. The 45 trusses 39 are connected by the transverse girders 46 which are spaced a distance substantially equal to the width of the recesses 41. These girders carry the center plate support 47 and this plate is reinforced by the 50 diagonal braces 48 extending from the corners of the plate to the junctures of the trusses and the beams 38. As shown in Figure 8 these braces 48 are substantially of inverted U-shape in cross section.

55 The beams 38 have their outer sides adjacent the ends thereof formed with the vertical channels or grooves 49 to receive the projections 28, thus providing a more or less loose connection between the side frames and 60 bolster to hold the side frames in proper spaced relation. It will be observed, as the bolster is of one piece construction, the channels 49 are provided on one side only of each of the beams 38, the opposite sides having 65 no engagement whatever with the side

frames. The trusses 39 are connected to and extend between the sides of the beams 38, that is to say, the trusses are not secured to the upper faces of said beams. Furthermore the transverse girders 46 are connected to 70 and extend between the adjacent sides of the trusses 39.

The ends of the beams 38 are supported on the equalizer bars E by means of the coil springs. 75

Although an embodiment of the invention has been described in detail, it is to be understood that the invention is not thus limited, but includes modifications and changes which come within the scope of the 80 appended claims.

Having thus described the invention what is claimed as new and desired to be secured by Letters Patent is:

1. A six wheel freight truck including in 85 combination, side frames, journal boxes for the end axles secured to the under side of said frames, journal boxes for the central axle, a pair of equalizer bars at each side of the truck each supported at one end on 90 the central journal box, said ends cooperating with the said central journal boxes and frames, to hold said boxes against movement transversely of the truck and bolster means supported by said bars. 95

2. A six wheel freight truck including in combination, a pair of side frames supported on the journals of the end axles, each frame having a depending projection adjacent each end journal, equalizer bars, each having one end supported on a journal of the central axle and its other end carried by one of said projections, a truck bolster supported on said bars including two transverse beams secured together, each of said beams adjacent 105 its ends having a single tongue and groove connection with said projections constituting the sole means connecting said frames. 100

3. A six wheel freight truck including in combination, a pair of side frames supported 110 on the journals of the end axles, equalizer bars, each having one end supported on a journal of the central axle and its outer end carried by the frame at a point adjacent a journal on an end axle, a truck bolster supported on said bars including two transverse beams secured together, each of said beams adjacent its ends having a laterally disposed single tongue and groove connection with the frames whereby the frames are held 115 120 properly spaced.

4. A six wheel freight truck including in combination, a pair of side frames, journal boxes for the end axles bolted to the under sides of said frames, a projection depending 125 from said frames adjacent each of said boxes; equalizer bars each having an end supported on a journal of the central axle, and an opposite end carried by one of said projections; a bolster including two trans- 130

- verse beams integrally connected together resiliently supported on said bars, each beam adjacent each end having a single laterally disposed vertical channel receiving one of 5 said projections, said grooves and projections constituting the only means connecting said frames.
5. A one piece bolster for six wheel freight trucks comprising two parallel transverse 10 beams, spaced parallel longitudinal trusses connecting said beams, each truss having a recess substantially midway of its length opening downward for the central axle, a center plate, and means to support the same 15 including centrally disposed transverse girders connecting said longitudinal trusses and reinforcing straps secured to the underside of said trusses and spanning the mouths of said recesses.
- 20 6. A bolster construction for six wheel freight trucks comprising two parallel transverse beams, spaced parallel longitudinal trusses connecting said beams, each truss having a recess on its under side substantially midway of its length for the central axle, and a center plate supported on said trusses and braced by diagonal members extending from the plate to the juncture of the beams and trusses and reinforcing 25 straps bolted to the underside of said trusses and spanning the mouths of said recesses.
7. A one piece bolster for six wheel freight trucks comprising a pair of substantially straight transverse beams, a pair of 30 parallel spaced longitudinal trusses connected to, and extending between the adjacent sides of said beams, said trusses being set back from the ends of the beams, each truss having a recess substantially midway 35 of its length opening downwardly for the central axle, a reinforcing strap secured to the under side of said trusses and spanning the mouths of said recesses, the outer sides of said beams having vertical channels adjacent 40 their ends adapted to cooperate with the side frames of the truck and constituting the sole direct connections therebetween, and a center plate supported on said trusses.
8. A bolster for six wheel freight trucks 45 comprising a pair of substantially straight transverse beams, a pair of longitudinal trusses connected to, and extending between, the adjacent sides of said beams, said trusses formed with downwardly opening recesses 50 for the central axle, a pair of girders connecting said trusses being spaced substantially the width of said recesses, one on each side thereof and a center plate carried by said girders, all said parts constituting a 55 single piece, and reinforcing straps secured to the underside of said trusses and spanning the mouths of said recesses.
9. A six wheel freight truck including in 60 combination, one piece side frame members, equalizer bars, each having one end sup-
- ported on a frame member and the other end on a journal box of the center axle, said box having a recess to receive said end and said frame member also having a recess receiving a portion of said end whereby 70 said end constitutes a key holding said box and frame member against relative transverse movement.
10. A six wheel freight truck including in combination, one piece side frame members, equalizer bars, each having one end supported on a frame member and the other end on a journal box of the center axle, and means to hold said journal box against transverse movement including the associated 75 ends of said bars.
11. As an article of manufacture, a single piece side frame member for railway trucks, said member being of hollow box section construction and straight throughout the greater part of its length, the end portions being tapered and inclined downwardly to a level below the bottom of said straight part.
12. As an article of manufacture, a single piece side frame member for railway trucks, said member being of hollow box section construction and straight throughout the greater part of its length, the end portions being tapered and inclined downwardly to a level below the bottom of said straight part, said tapered portions adapted to have journal boxes secured to their under sides.
13. As an article of manufacture, a single piece side frame member for railway trucks, said member being of hollow box section construction and straight throughout the greater part of its length, the top and bottom walls being substantially straight and parallel, the end portions being tapered and inclined to the straight part, said member adapted to have journal boxes secured to its under side, and also constructed to support one end of each of a pair of equalizer bars.
14. As an article of manufacture, a single piece side frame member for railway trucks, said member being hollow and straight throughout the greater part of its length and formed with a longitudinal slot in its under side substantially midway of its length adapted to receive a projection to hold the central box against transverse movement, said frame also constructed to have journal boxes secured to its under side and to support one end of each of a pair of equalizer bars.
15. As an article of manufacture, a single piece side frame member for railway trucks, said member being of hollow box section construction and straight throughout the greater part of its length, the end portions being tapered and inclined in one direction to the straight part, and the tips of said end portions being offset from the straight part in another direction.

16. A six wheel freight truck including in combination, side frame members, equalizer members, each having one end supported on a frame member and the other end on a journal box of the center axle, a bolster carried by said equalizer members and holding the side members spaced, means to hold the center journal boxes against any substantial axial movement comprising means securing an equalizer member and a center journal box for movement together transversely of the truck, and cooperating means on the frame and equalizer members to hold the equalizer members against such transverse movement. 10
